UNITED STATES PATENT OFFICE.

JOHN E. BUXTON, OF OWATONNA, MINNESOTA.

GRAIN-BINDER.

SPECIFICATION forming part of Letters Patent No. 248,401, dated October 18, 1881.

Application filed April 23, 1881. (Model.)

To all whom it may concern:

Be it known that I, JOHN E. BUXTON, a citizen of the United States, residing at Owatonna, in the county of Steele and State of Minnesota, have invented certain new and useful Improvements in Grain-Binders; and I do hereby declare the following to be a full, clear, and exact description of the invention, such as will enable others skilled in the art to which it applies to make and use the same, reference being had to the accompanying drawings, and to letters or figures of reference marked thereon, which form a part of this specification.

Figure 1 is a perspective view of the device. Fig. 2 is a top-plan view. Fig. 3 is a central cross section on line $x' x'$ of Fig. 2. Fig. 4 is a bottom plan, showing the springs which help actuate the needle and cord moving arm. Fig. 5 is a detail view showing the knotter. Fig. 6 is a detail view showing the connection between shafts E' and I. Fig. 7 is a detail view, in side elevation, showing some of the operative parts.

The present invention relates to that class of grain-binders known as the "cord" or "twine" binders; and the novelty consists in the detail of the construction and the combination of the parts which compose it, as will now be set forth in detail.

In the accompanying drawings, A denotes any suitable frame or carriage in which the binder is mounted; and B, the usual floor, properly shaped to allow easy passage for the grain from the reception to the delivery end.

The packer-arms c are curved projections extending from a disk, C, two or more of which disks are mounted on a horizontal shaft, D, extending from side to side of the machine. Motion is given to this by any suitable power.

As the grain is delivered in the machine it is carried forward by the revolving fingers c until sufficient has accumulated to form a bundle or gavel, when the mass will press so hard against the compressor-arm E in the rear part of the machine as to force it outward. This communicates motion to the shaft E' in the upper and rear part, and causes the cam F at its end to turn slowly forward. The pin g of the pivoted arm G moves in the slot f of said cam, swinging said arm horizontally against the clutch-wheel H on shaft I, which is revolved

by proper connection with the main shaft D, and causes it to engage with the part i of the clutch fixed on said shaft, and thus motion is carried by the arm i' and link K to the arm m of the bent shaft m', connected with curved needle-arm M. Thus said arm M is raised up through the slot b in the floor of the machine and pressed against the gavel, forming it into a proper shape and carrying the cord over the bundle. The cord is brought over the revolving knotter N, which has an open-mouthed cutting-notch, n, in it for the purpose of holding the cord. This knotter has a pinion, n', on its shank, and is so mounted in the frame that it is actuated by the segment-gear o on the wheel or disk O, which has motion together with the shaft I through the part i and wheel H. The segment-gear is so arranged that it actuates the knotter just as the needle-arm has brought the cord into proper position over the gavel or bundle to be tied. The cord is held between the grasper-bar P and the slotted arm R, and is cut by the V-shaped knife p of the grasper-bar.

The spring r serves to keep the holder normally away from the knotting-hook and to allow it to be moved up slightly toward the hook as the cord is needed in the operation of tying the knot, said movement being caused by the pull on the cord as it is being looped around the knotter. The action of the spring then is to cause the knot to be tied closely and under tension. The holding and cutting bar is slid forward as the knot is completed, so as to release the old end and allow the cord extending from the point of the binder-arm to the knotter to fall into the notch in said bar. The bar is then retracted, and the cord is thereby cut on the side toward the knotter and clamped on the other side, ready for another binding operation. While the gavel is being delivered from the machine the raised portion or segmental projection o' on the wheel O bears against the straight side of the semicircular revolving portion n'' of the head of the shaft of the knotter N, and thus the knotter is held firmly in position, as now shown in Fig. 3. So soon as this projection o' passes by this side of n'' the rack o on the wheel O actuates the pinion n' and revolves the knotter, and when the rack ceases to operate, the arm i' on the shaft comes against

the flange n''' on said piece n'' , and gives it a quarter-turn back, placing it in position to be reversed when the end of said portion o' strikes it and acts on it, as above described. By the 5 retracting motion communicated to the grasper-bar P from the lever q, to which it is pivoted, and which is moved by the cam-slotted wheel Q, revolved by shaft I, on which it is fixed, the cord is drawn through the cutter-slot r' in the 10 arm R and severed. Simultaneously, or nearly so, with this act the arm I' on the shaft I, which has been slowly moving under the projection e of the compressor-arm E, is released therefrom, and motion is communicated to the shaft 15 E' by the link S, connecting with the crank-arm e' at the end of the shaft, and actuated by the spur-wheel t on the end of shaft I, engaging with its hooked bent end. This revolution of the shaft E' causes the arm E to be moved outward and brings the arms U, which project upward and inward from said shaft E', into the rear of the gavel or bundle, and these then carry it forward and out of the machine. When 20 the two arms throw the bundle from the machine the knotter turns one-fourth round and the knot is drawn off the knotting-hook, and by means of the sharp edge in the point of knotting-hook the loop or tongue is cut and clears itself from the knotter, so if the sharp 25 edge should not cut the loop the loop will slip out of the front when the knotter is reversed into position at right angles with the needle-arm.

It should be noted that the action of the 30 cam-arm I' causes at first the compressor-arm to be brought slightly toward the needle-arm, and thus insures the packing together and shaping of the gavel.

The flaring or flanged ends u of the delivery- 35 arms U materially aid in the effectual and safe delivery of the bundle from the machine.

At each side of the floor of the machine are 40 spring guide-arms V, which are hinged at the rear end and project out to the front, and are 45 adapted to be set at any desired angle by the rod v and screw v'. As the gavel comes into the narrowing passage made by these spring-guides the grain is brought lengthwise into even and good shape. When the cam-arm I' is 50 released from the projection e of the compressor-arm, the crank-arm i, by its travel, causes the arm m beneath the floor of the machine to 55 retract the needle-arm M, which is accordingly carried down through the slot b under the machine and into position to be again brought forward and operated as above set forth.

The cord-moving arm W is notched on its end, and acts in conjunction with the needle-arm M in the usual manner. The springs x on the 60 shafts of needle-arm and cord-arm W insure the efficiency of their operation.

The guide-rods y will serve to keep the grain from getting into the machinery as it passes along from its delivery to the exit end. The 65 hinged plate or leaf z, under the packer-wheel C, has springs z' to keep it level with the floor

of the machine. When this plate is hinged at its lower edge the springs will be so placed as not to throw the upper edge of the plate above the bed or floor. It may sometimes be found 70 advisable to hinge the plate on its upper edge and let the springs act on the lower. The detail of all this construction will readily suggest itself to any one skilled in this class of devices. This plate is of value when wet or 75 matted grain or any clogging substance is passed under the packing-fingers, as it will give sufficiently to prevent any accident to the said fingers or machine.

The spring x' on the shaft E serves to press 80 the shaft over, so as to insure the action of the cam F. The spring x'' causes the arm S to act with certainty.

The ends of the compressor-arm E may be 85 made a little flaring, to insure its efficient action.

The packer C, being made of a solid disk and having the projections or arms c, will be found exceedingly strong and durable.

Having thus described my invention, what 90 I consider new, and desire to secure by Letters Patent, is—

1. The knotter N, having an open-mouthed cutting-notch, n, in its lower end, and pinion n', combined with the wheel O, having gear o 95 and projection o', and grasper P, having knife p, and bar R, slotted at r', all substantially as and for the purposes set forth.

2. The combination of arms E and U, shaft E', cam F, clutch H, piece i, and pivoted arm 100 G, with shaft I, needle-arm M, connected with and operated by said shaft I, substantially as shown and described.

3. In combination with the revolving packer C, a hinged section, z, or portion of the floor of 105 the binder provided with a spring, substantially as shown and described.

4. In combination with the floor B, the spring guide-arms V at the side, adjustable by rods v and set screws v', substantially as set 110 forth.

5. The knotter N, having pinion n' and the open-mouthed cutting-notch n, at its lower end, all substantially as shown and described.

6. The combination of arms E and U, shaft 115 E', cam F, clutch H, piece i, pivoted arm G, and shaft I, with grooved wheel Q, lever q, grasper P, having knife p, bar R, and spring r, substantially as set forth.

7. In a grain-binder, the combination of the 120 needle-arm M, compressor-arm E, and discharging-arm U, each operated as described, with a knotter, N, having cutting-notch n and pinion n', and grasper P, slotted bar R, spring r, wheel Q, and lever q, substantially as described.

In testimony whereof I affix my signature in presence of two witnesses.

JOHN E. BUXTON.
